UNITED STATES PATENT OFFICE.

ALFRED AMOS LEWIS, OF MELBOURNE, AND FREDERICK O. DUTTON, OF NORTHCOTE, VICTORIA, AUSTRALIA.

SAFETY DEVICE OR APPLIANCE FOR USE WITH AEROPLANES, AIRSHIPS, AND OTHER AIRCRAFT.

1,339,828.

Specification of Letters Patent. Patented May 11, 1920.

Application filed October 12, 1918. Serial No. 257,899.

To all whom it may concern:

Be it known that we, ALFRED AMOS LEWIS, residing at 349 Collins street, Melbourne, in the State of Victoria, Commonwealth of 5 Australia, and FREDERICK OLIVER DUTTON, residing at 29 Leonard street, Northcote, in the State of Victoria, aforesaid, both subjects of the King of Great Britain, have invented new and useful Improvements in 10 Safety Devices or Appliances for Use with Aeroplanes, Airships, and other Aircraft, of which the following is a specification.

This invention relates to an improved device or appliance for use with all forms of 15 aircraft, and it has been devised in order to provide efficient means whereby an aeroplane, dirigible balloon, airship or the like can in the event of accident or of stoppage be permitted to descend gradually without 20 damage to the machine or injury to the occupants thereof.

An essential feature of the invention resides in the provision of spring operated means whereby the device can be brought 25 into operation immediately following an accident or other cause for descent and before any high velocity is attained. Means are also provided for the regulation of the speed of descent as may be desired.

30 In addition to the use of the invention with aircraft for the purposes set out it may be employed with or applied to parachutes for the purpose of materially increasing the safety of such devices.

35 In order that the invention may be readily understood reference will now be had to the accompanying explanatory drawings; wherein:—

Figure 1 is a view in vertical section of a 40 safety device constructed according to the invention.

Fig. 2 is a view in perspective illustrating an application to an aeroplane of the safety device shown in Fig. 1.

45 In these drawings the numeral 1 designates a pole or mast of suitable wood or metal, the upper end of which is furnished with a band 2 or the like which is firmly fixed thereto. This band 2 is provided with 50 a series of lugs 3 to which are pivotally connected a plurality of strong flexible ribs 4 preferably made of steel.

The lower ends of these ribs are provided

with eyes 5 to which are attached strong cords or ropes 6 which connect said ribs 4 55 to a second band 7 firmly attached to the lower portion of said mast 1. This band 7 is likewise provided with lugs 8 to which the cords or ropes 6 are attached.

A strong textile covering forming a hood 60 or envelop 9 of canvas, silk or other preferred material of required strength is placed upon and over the ribs 4 and is secured thereto in an approved way.

A sleeve 10 is slidably mounted on the 65 mast 1 and this sleeve 10 is provided with a series of circumferentially disposed lugs 11 to which are pivotally connected a plurality of stays or struts 12. These stays or struts 12 correspond in number to said ribs 4 and 70 each of said stays or struts is pivotally attached as at 13 to one of said ribs at or about the middle point thereof.

The sleeve 10 is provided with a collar 14 or the like which, when the sleeve 10 is at 75 its lowest position, engages with catches 15 formed on the ends of a pair of diametrically opposite levers 16 pivoted on a band 17 fixed to said pole or mast 1.

Springs 18 are inserted between the levers 80 16 and the band 17 and the lower ends of said levers 16 are shaped to form operative handles 19. A plurality of strong springs 20 are attached at their lower ends to lugs 21 or the like on said sleeve 10. These 85 springs 20 are connected at their opposite ends to similar lugs 22 on said band 2.

In practice the sleeve 10 is moved to its lowest position indicated by broken lines in Fig. 1, thereby tensioning said springs 20 90 and permitting the springs 18 to operate the levers 16 and effect engagement of the catches 15 with said collar 14.

The descent of said sleeve 10 by means of the stays or struts 12, draws the ribs 4 inwardly, and in the lowest position of said sleeve 10 said ribs 4 and struts 12 lie closely alongside the central pole or mast 1, and maintain the hood or envelop 9 in a collapsed state.

100 In the event of accident or stoppage when it is required to operate the device, the handles 19 are simultaneously moved inwardly toward the pole or mast 1 so as to move the catches 15 out of engagement with the collar 105 14 and release said sleeve 10. The latter is

at once drawn upwardly by said springs 20, and the ribs 4 are at the same time forced outwardly by said stays or struts 12, thereby expanding the hood or envelop 9 into a 5 dome-shaped form.

The hood or envelop 9 at the top adjacently to the upper end of the pole or mast 1 is provided with one or more regulating valves 23 of approved pattern which can be 10 opened by cords 24 or the like more or less widely to control the speed of descent.

The device can be attached to the upper-side of an aeroplane or other air craft as shown in Fig. 2, or it may be attached to an 15 aviator's seat which can be detached from the aircraft in the event of accident.

The invention can, moreover, be arranged and constructed as a parachute and can be provided with seating or other accommodation 20 commonly furnished for a balloonist.

It will be understood that the device can be released and retained in its expanded position under normal traveling conditions, and in such expanded position it will act as 25 a covering or canopy which will be a protector against rain and other adverse climatic conditions.

The invention is of simple construction, and can be made of great strength, and in 30 operation it will be found very efficient as a means for preventing damage to aircraft or injury to persons traveling therein in the event of accident or stoppage.

A pair of flattened springs 25 are fixed to 35 the mast 1 and the upper ends of these

springs 25 are adapted to bear against the lower end of the sleeve 10, and prevent oscillatory movements of the latter when the hood sleeve 9 is in an expanded state. Shallow slots (not shown) are made in the side 40 of the mast 1 into which the springs are forced when the sleeve 10 is moving upwardly or downwardly.

What we do claim is:—

A safety device for aircraft comprising a 45 mast, ribs pivotally secured to the upper end of said mast at one end and the opposite ends secured to the mast by cables, a sleeve 50 slideable on the mast, struts pivotally connected to said sleeve at one end and at the opposite ends to the ribs, a spring coiled about the mast and confined between the connection of the ribs thereto and the sleeve and tensioned to normally urge the sleeve to position to move the struts and ribs to open 55 position, a covering for the ribs, latches pivotally carried by the mast adapted to co-operate with the sleeve to hold the same in position with the struts and ribs in collapsed position, openings in the covering for the 60 ribs, and flap valves operable to open and close said openings for the purpose specified.

In testimony whereof we affix our signatures in presence of two witnesses.

ALFRED AMOS LEWIS.
FREDERICK O. DUTTON.
